UNITED STATES PATENT OFFICE

2,583,522

FLUID PURIFIER

Charles A. Winslow and John J. Meyer, Alameda County, Calif., assignors to Winslow Engineering Co., Oakland, Calif., a partnership

Application April 27, 1948, Serial No. 23,558

2 Claims. (Cl. 210—1.5)

1

This invention relates to an improved purifier for removing particles of foreign matter from fluids. More particularly it relates to a controlled-flow, magnetic liquid purifier. Still more particularly it relates to a combination of magnetic purifying means with a flow-control screen for the removal of both ferromagnetic and non-magnetic solid particles from liquid.

Purifiers embodying the principles of this invention are particularly useful in circulating lubrication systems, where it has been particularly difficult to free the oil from particles of iron and other ferromagnetic metals and alloys. Screens have been used in the attempt to remove these particles but most of them are so small that they pass through even fine mesh screens, and do great damage to bearings and lubricated moving parts. Attempts have also been made to remove these ferromagnetic particles from the circulatory system by such magnetic means as magnetic drain plugs, but with indifferent or incomplete success. The principal reason for failure has been that they subject only a small percentage of the oil to the magnetic field. For example, magnetic drain-plugs have been employed in sumps, on the theory that the particles are heavier than the oil and that as they settle they will come into the magnetic field, be attracted, and then held. However, most of the particles do not settle, due to their small size and to the viscosity of oil, and so they are not removed. The problem has been to secure a flow control means which subjects substantially all the ferromagnetic particles in the oil stream to the action of the magnetic field. One object of this invention is to solve the above problem.

Another object of the invention is to provide an improved magnetic means of removing ferromagnetic particles from fluids.

Another object of the invention is to provide a purifier which subjects substantially all of a flowing liquid to the action of a magnetic field.

Another object of the invention is to provide a controlled-flow, magnetic purifier.

Another object of the invention is to provide a magnet-strainer combination which removes all types of solid matter from fluids.

Another object of the invention is the provision of a self-washing action of the screen and magnet by the fluid being filtered and cleaned.

Another object of the invention is the provision of means for concentrating collected material, magnetic and otherwise, in a sump out of the path of fluids being filtered.

Another object of the invention is the provision of a blow-off means for cleaning the magnet, screen, and sump of collected material by pressure during operation.

A further object is to provide a magnet strainer unit well suited for quick installation and removal, easily cleaned or replaceable.

Other objects and advantages of the invention

2

will appear from the course of the following description, which is presented in accordance with U. S. Revised Statutes, section 4888. The specific embodiment herein described is not intended to limit narrowly the claims to the invention.

In the drawings:

Fig. 1 is a view in elevation and in section of a purifier embodying the principles of the invention;

10 Fig. 2 is a view taken along the line II—II of Fig. 1; and

Fig. 3 is a sectional view on the line III—III of Fig. 1.

Basically the invention comprises a controlled-flow magnetic purifier designed to be installed in a passage having an inlet and outlet and a drain.

The purifier includes a support member mounting a plurality of permanent magnets so disposed as to present maximum distribution and strength of field. Surrounding the magnet-member is a fine mesh screen which divides the passage into two chambers, separates the inlet and the magnet from the outlet, and controls the flow of fluid so that substantially all the fluid passes through the magnetic field while passing in from the inlet and out toward the outlet through the screen.

The preferred embodiment shown in the drawings utilizes a hollow, generally cylindrical housing 10. At one end of the housing 10 is a horizontal, axial boss 11. The boss 11 is axially bored to provide an inlet opening 12 which is internally threaded to receive an inflow conduit 13 and provide a passage which introduces fluid into the chamber 14 inside the housing 10.

30 Around the inlet 12 and projecting into the chamber or passage 14 is an annular, tapered shoulder 15. On the body of the housing 10 and adjacent the end 16 opposite from the inlet 12 is a vertical boss 17. The boss 17 is bored to provide an outlet opening 18 which is internally threaded to receive an out-flow conduit 19.

The end 16 of the housing 10 is closed by a hollow cap 20, which is held by a plurality of bolts 21 threaded into the lip of the housing. The cap 20 is formed with an annular flange 22 which projects into the passage 14 and a threaded boss 222 on the opposite side, the flange's outside edge abutting a shoulder 23 on the housing body.

45 The central portion of the cap 20 is provided with ribs 200 and in the center by an inside central boss 24, in which is a threaded axial recess 25.

The inside edge of the flange 22 supports and encloses one end of a cylindrical screen 30, and when the cap 20 is in place, the other end of the screen 30 rests on and is closed by the outside, tapered edge of the annular shoulder 15. The screen 30 divides the passage 14 into an interior chamber 31 communicating with the inlet 12 and 50 an exterior annular chamber 32, communicating with the outlet 18. Like all the components of

the purifier except the actual magnet elements, the screen 30 is made of non-magnetic material, and preferably is of fine mesh. Thus, the screen 30 acts not only as a screen to remove non-magnetic foreign matter from the oil as it passes from the inlet to the outlet, but also as a flow control. The fine gauge screen restrains the fluid sufficiently so that it passes from the inside chamber 31 to the outside chamber 32 along the full surface of the screen 30, with the result that the flow tends to be more strongly axial and less strongly radial or outward. This action tends to flow impurities along with the fluid toward the sump 201 where they may be readily blown out during operation by opening the valve 202. Axial flow in the casing thus assuring introduction of the oil into the magnetic field, can be further obtained by substantially equating the force necessary to flow the oil through the screen, to the fluid flow in the system, the actual force depending on the oil pressure and velocity in the system, the total area of the screen openings and the total resistance to flow through all the small openings.

The ribs 200 in the cap 20 supports in the center chamber 31 a magnet assembly, shown generally at 40. The assembly 40 comprises a non-magnetic rod 41, threaded into the axial tap 25 and steadied against the boss 24 by the nut 42. Mounted on the rod 41 are a plurality of alternately-positioned magnetic elements 43 and non-magnetic spacing members 44. A nut 45 and washer 46 on the end of the rod 41 hold the elements 43 and spacers 44 in prearranged, fixed positions. Each individual magnetic element 43 is shaped as shown in Fig. 2—a torus or annulus broken at one end, to form a round, horseshoe magnet with the north and south poles separated by a gap 47. When the elements 43 are placed on the rod 41, they are disposed so that the poles face in all different directions and provide a substantially uniform field of at least the radius of the chamber 31. By using a plurality of magnetic elements 43 in the assembly 40, a much stronger and more even field is obtained than can be obtained by using a single bar magnet similarly disposed. Since the volume of the magnetic field equals or is greater than the volume of the chamber 31, every ferromagnetic particle passing from the inlet 12 to the outlet 18 enters the magnetic field and becomes subject to it at the same time that the fluid momentum is restrained within the limits of the magnetic field by the screen 30.

On operation, the oil flows through the central inlet 12 into the chamber 31. The screen 30 controls its flow, making it substantially axial over most of the length of the chamber 31 and subjecting it to the overall field of the magnet assembly 40. The ferromagnetic foreign matter is attracted to and held by the individual magnet elements 40. The flow control screen 30 also serves to filter out the solid non-magnetic particles from the oil, and heavy particles are washed along toward the sump 201 and away from the inlet 12. As the oil passes generally axially along in the chamber 31, it gradually flows at its outer edge out through the screen 30 into the outer chamber 32 and thence to the vertical outlet 18, purified of the solid particles and especially of the ferromagnetic particles.

The mounting of both the screen 30 and magnet assembly 40 on the hollow cap 20 renders withdrawal, replacement, and cleaning simple. When the screws 21 are taken out, the purifier

may be withdrawn from the housing. The screen 30 can be pulled out from the cap flange 22, and it and the magnet assembly 40 brushed off, reassembled, and the whole purifier then put back in the passage 14. It will be understood that axial direction of fluid flow and velocity of same causes all material collected which is not firmly held by the magnets to be collected in the sump 201. It is to be further understood that when the invention is used under pressure that opening of the valve 202 would cause all collected material not firmly attached to magnets to be blown out through the opening 203, thus cleansing the screen 30 and magnets 93, as well as removing all other collected material in the sump 201 and chamber 31.

We claim:

1. A magnetic filtering device for flowing fluids comprising an elongated housing having a cylindrical walled chamber therein, an inlet opening in one end of the housing co-axial with said chamber, an outlet opening from said chamber in the side wall of the housing, a cap removably secured to the opposite end of the housing and having a cylindrical flange extending within said chamber, a boss rigidly supported within said cap in co-axial relation to said inlet opening and said cylindrical flange, an elongated magnet assembly disposed within the chamber and having one end thereof removably supported by said boss, said housing being also provided with an inwardly directed flange surrounding said inlet opening and provided with an outer frusto-conical wall converging toward said opposite end of the housing and being in co-axial relation to said cylindrical flange, the inner converging end portion of said wall being of less diameter than the inner surface of said cylindrical flange, and a cylindrical filter screen having one end thereof removably seated within said cylindrical flange and its opposite end freely engaged over said frusto-conical wall, whereby said screen is removable as a unit with said cap and concentrically supported with respect to said magnet assembly by said frusto-conical wall.

2. The device according to claim 1, wherein said magnet assembly comprises an elongated non-magnetic rod, having one end thereof threaded into said boss, and the opposite end thereof freely disposed adjacent the inner end of said inwardly converging flange, a plurality of horseshoe magnets supported on said rod, a plurality of non-magnetic spacing members disposed on said rod between said magnets for maintaining same in uniformly spaced relation, and said magnets being arranged on the rod with their poles facing in different directions radially of the rod for providing a substantially uniform magnetic field about the magnet assembly and within the screen.

CHARLES A. WINSLOW.
